Filed Dec. 11, 1964, Ser. No. 82,990

Term of patent 14 years

(Cl. D52—2)

FIG. 1

FIG. 2

FIG. 3

FIG. 4

FIG. 5

FIG. 6

FIGURE 1 is a front elevational view of a butter pat dispenser, showing my new design;

FIGURE 2 is a rear elevational view;

FIGURE 3 is a cross-sectional view thereof, taken on line III—III in FIGURE 2;

FIGURE 4 is a top plan view thereof, a portion of the cover being broken away for convenience of illustration;

FIGURE 5 is a front perspective view thereof with the cover omitted and the transparent front panel in a raised position; and

FIGURE 6 is a rear perspective view thereof with the cover omitted and the butter pat container in a raised position.

The broken line representation of butter pats and their packages in FIGURE 1 is for purposes of illustration only.

I claim:

The ornamental design for a butter pat dispenser, as shown and described.
